(57) **CLAIM**

The ornamental design for backpack with a visual element, as shown and described.

DESCRIPTION

This application claims the benefit of U.S. Provisional Patent Application No. 60/487,730, filed on Jul. 17, 2003, the contents of which are incorporated herein by reference thereto.

FIG. 1 is a left perspective view of a backpack with a visual element showing my new design in use; the broken line showing a child, fastener pulls, and straps, forming no part of the claim;

FIG. 2 is a front elevational view thereof;

FIG. 3 is a left side elevational view thereof, of which the right side elevation is a mirror image;

FIG. 4 is a rear elevational view thereof;

FIG. 5 is an enlarged fragmentary view of the front pocket panel shown in area 5 of FIG. 1; and,

FIG. 6 is an enlarged fragmentary elevational view of the side pocket panel shown in area 6 of FIG. 1.
